E. W. KRAUSS

TROLLEY AND TELEGRAPH POLE

Filed Aug. 23, 1924

Patented Mar. 24, 1925.

UNITED STATES PATENT OFFICE.

EARL W. KRAUSS, OF CLYDE, OHIO.

TROLLEY AND TELEGRAPH POLE.

Application filed August 26, 1924. Serial No. 734,265.

To all whom it may concern:

Be it known that I, EARL W. KRAUSS, a citizen of the United States, residing at Clyde, in the county of Sandusky and State of Ohio, have invented certain new and useful Improvements in Trolley and Telegraph Poles, of which the following is a specification.

This invention relates to improvements in poles adapted for the support of trolley and telegraph wires.

An object of the invention resides in providing a pole construction of the type above mentioned, having a permanent base adapted to be embedded in the ground carrying anchor bolts adapted to mount a reinforced pole construction, having a pair of angle bars secured in spaced parallel relation at predetermined points throughout their length by suitable means adapted to form stirrups to provide for the convenient climbing of the pole, and means for mounting said spaced bar members on said base including a reinforced base mounting carrying said base bar and adapted for removable attachment to the anchor bolt of the pole base embedded in the ground, said parallel bars adapted to removably receive suitable cross arms for carrying the insulators to which the telegraph, telephone, or trolley wires may be attached.

The invention also includes other objects and improvements in the details of construction and arrangement of the parts which are more particularly pointed out in the following description and claims, directed to a preferred form of construction, it being understood, however, that various changes in the specific details and arrangement of parts may be made, without departing from the scope and spirit of the invention as described and claimed.

In the drawing, forming a part of this application:

45 Figure 1 is an elevational view of the improved pole construction.

Figure 2 is another elevational view, taken at right angles to Figure 1, of said pole construction.

50 Figure 3 is a plan view looking down on top of the pole and illustrating the manner of securing the upper cross arm thereto.

Figure 4 is a sectional view, taken on the line 4-4 of Figure 2.

55 Figure 5 is a sectional view, taken on the line 5-5 of Figure 2.

1 indicates the pole base, preferably formed of reinforced concrete, which is adapted to be embedded in the ground to provide a permanent base, where it is desired to mount or position a pole for the support of telegraph, telephone, or trolley wires. A plurality of anchor bolts 2 are positioned in the base, and have the threaded end portions thereof projecting upwardly from the upper end thereof, in a manner as clearly illustrated in Figure 1 of the drawings to receive nuts for a purpose to be set forth.

A mounting structure is indicated at 3, 70 for the pawl, which includes a plate 4, provided with a plurality of openings adapted to receive the upwardly extending ends of the anchor bolt 2, extending above the upper end of the pole base 1. An upright member 5 of H-section is mounted in vertical relation on the bottom plate 4 and is secured thereto by angle plates 6, suitably riveted to the member 5 and secured to the plates 4, through the medium of the anchor 80 bolt 2, thereby forming the mounting structure 3 for the pole structure to be presently described.

The main pole structure includes a pair of angle bars 7, having one side of each 85 mounted in spaced parallel relation, and riveted, or otherwise secured to the web portion of the member 5, while the divergent sides of the angle bar are arranged in the same plane and are secured to one side of 90 the member 5, by riveting, or otherwise, as clearly illustrated in Figures 1 and 2, so that the angle bars 7 are rigidly mounted and supported in a vertical position on the pole base 1, through the medium of the 95 mounting structure 3.

Spacing members 8 are positioned between the adjacent parallel flanges of the angle bars 7 of the pole, and are formed with openings aligned with openings in said parallel flanges adapted to receive the shorter leg 9, of a U-shaped stirrup member 10, which is provided at the end of the longer leg thereof with an upstanding terminal 11, to complete the stirrup of said 100 member, the shorter leg being threaded as indicated for receiving the nut 12, adapted for securing the spacing members in place, and for holding the adjacent parallel flanges of the angle bars 7, in rigid spaced 105 relation. These stirrups and spacing members are secured throughout the length of

the cross bars 7 at the proper spaced intervals, in order to provide the proper number of stirrups so that the pole may be easily climbed in order to provide access to the 5 cross arms thereon, supporting the telegraph, telephone, or trolley wires.

A cross bar is mounted in the central portion of the height of the pole as indicated at 13 and extends between the adjacent flanges 10 of the bars 7, and is secured thereto by suitable bolts 14, the ends of said bar receiving angle irons 15, which are adapted to project therefrom a suitable distance for receiving the supporting insulator for trolley wires.

15 When it is desired to support telegraph and telephone wires on said pole, an angle plate 16 is provided, adapted to be fitted against the diverging sides of the angle bars 7, and has one flange thereof formed with 20 an opening to receive the head 17, of a holding bolt, having the shank portion 18 thereof extended between the parallel flanges of the bars 7, and receiving beyond the free edges thereof a nut 19 in threaded cooperation therewith for securing said plate through the binding action of said hook bolt to said bars 7. A suitable cross arm 20 is provided with suitable openings for receiving bolts to secure the same to the angle 25 plates 16, in the manner illustrated in Figures 1 and 2, and is also provided with an opening in the central portion for receiving the shank portion of the hook bolt or securing member having the hook end 17. The 30 insulators for the telegraph or telephone wires are mounted in the usual manner on the outer end of this cross arm 20, in the usual manner. As many of these cross arms may be provided on the pole, as is found desirable 35 for the support of the required number of telephone and telegraph wires, which may be positioned in the usual spaced relation, one above the other, on the poles.

This pole construction is preferably constructed of all metal parts, in order to provide a substantially strong and lasting pole structure, which may be changed, by removing the mounting structure 3, when desired, from the base 1, in order that the length or

size of pole for the support of the desired 50 number of telephone, telegraph and trolley wires may be provided.

From the foregoing description, it will thus be seen that a relatively simple and convenient form of pole construction has been provided, which is assembled by suitable stirrup bolts providing means whereby the pole may be readily climbed for the usual purposes, and which is readily assembled thereby for receiving the cross arm structures heretofore 55 described.

What is claimed is:

1. A pole of the class described comprising a permanent base member adapted to be positioned for mounting the pole and carrying means whereby a pole structure may be secured thereto, a mounting structure 60 removably secured to said base member, and a pole structure carried by said mounting structure including spaced parallel bar members 65 rigidly secured to said mounting structure, stirrup members secured in spaced parallel relation throughout the length of said bar members for rigidly securing said members in spaced parallel relation throughout 70 their length, and cross arms removably secured to said bar members.

2. A device of the class described comprising a base member adapted for permanent mounting in a desired location, a mounting 80 structure having a base plate, a vertical member mounted on said base plate, means for securing said mounting structure to said base member, a pair of angle members 85 rigidly mounted in spaced parallel relation at one end to said mounting structure and to the vertical member thereof, spacing means positioned at predetermined points throughout the length of said bar members therebetween, stirrup members extending through 90 said bar members and spacing members, and locking said bars in spaced parallel relation throughout their length, and a plurality of cross arms removably and adjustably secured to said bar members.

In testimony whereof I affix my signature.

EARL W. KRAUSS.
